ATTORNEY.

UNITED STATES PATENT OFFICE.

FRED C. IMMELE, OF KANSAS CITY, MISSOURI.

CHILD'S TOILET SEAT.

Application filed August 24, 1927. Serial No. 215,136.

My invention relates to toilet seats and more particularly to children's toilet seats.

It is a purpose of my invention to provide a toilet seat of the above mentioned character that is made so that the same can be substituted for the usual cover member provided on ordinary toilet seats, and which will have the appearance of the ordinary cover member when in down position.

10 My improved child's toilet seat comprises a seat portion and a back supporting portion hinged thereto, said back supporting portion preferably being in the form of a lid or cover member for the seat. It is a purpose of my invention to provide, in a device of the above mentioned character, guard means comprising side members hinged to the back supporting portion, and engaging the seat portion when in operative position, and a 20 transverse member carried by one of said side members and detachably engaging the other side member.

The side members are preferably in the form of frames, and are preferably provided 25 with resilient means for urging the side members away from each other, thereby tending to hold the transverse portion of the guard means in engagement with a suitable formation on one of the side frames. The resilient 30 means furthermore tend to swing the side frames into a divergent relation when the device is unfolded and to swing the transverse guard member about its pivotal axis on one of the frames, so that these parts are out of 35 the way of the child when the same is being placed on the seat.

The seat portion is preferably provided 40 with a portion of greater thickness at the rear thereof for hinging the cover thereto, and said cover is recessed to accommodate the guard means in folded condition. An important feature of the invention is the provision 45 of recesses in the thickened portion of the seat to accommodate the portions of the side frames that engage with clips on the seat portion when in operative position. The frames are preferably provided with offset portions engaging these clips, and said offset portions enter said recesses when the device is folded 50 up, to thus permit the frames to be so made that the same will engage the seat portion with the back supporting portion or cover member in an upright position.

It is another purpose of the invention to 55 provide a device of the above mentioned char-

acter with a seat portion having the opening therein adjustable to different sizes. This is preferably accomplished by providing an inset in the seat portion that is annular in form and which is detachable therefrom to 60 enlarge the opening in the seat.

Other objects and advantages of the invention will appear as the description of the drawings proceeds. I desire to have it understood, however, that I do not intend to 65 limit myself to the exact details shown or described, but that I intend to include as part of my invention all such obvious changes and modifications as would occur to a person skilled in this art and as would fall within 70 the scope of the claims.

In the drawings:

Fig. 1 is a perspective view of my improved child's toilet seat;

Fig. 2 is a front elevation thereof with the 75 cover in raised position;

Fig. 3 is a section of the seat and cover portion with the guard omitted, the section being taken on a line corresponding to the line 3-3 of Fig. 1;

Fig. 4 is an enlarged perspective view of 80 one of the holding clips on the seat portion showing a fragment of one of the side frames;

Fig. 5 is an enlarged fragmentary sectional view taken substantially on the line 5-5 of Fig. 2, and

Fig. 6 is a fragmentary bottom plan view 85 of the seat portion.

Referring in detail to the drawings, my 90 improved child's toilet seat comprises a seat portion 10 and a cover portion 11 serving also as a back supporting or back-rest portion. The seat portion 10 is provided at the rear end thereof with a thickened portion 12, which may be of any desired construction, being shown as being made of a 95 ply of material of a thickness corresponding to the thickness of the cover member 11. The cover member 11 is hinged to the seat portion 10 by means of the hinges 13, and a shoulder 14 is provided at the junction of the thickened portion 12 and the main body portion 100 of the seat 10.

The cover member 11 is provided with a depression or recess 15 in the under side thereof, said recess being substantially rectangular and opening into the face of the cover member 105 lying adjacent the shoulder 14. Mounted in the recess 15 near the opposite sides thereof

are the hinge members 16 that are provided with the tubular portions 17. Guard means for preventing the child from falling off the device are provided, said means comprising a pair of side frame members 18 having the vertically extending portions 19 pivotally mounted in the tubular portions 17 of the hinge member 16. The side frames are substantially rectangular, the lower members 20 of each of the frames, being inclined slightly downwardly toward the forward ends of the frames, and being provided with downwardly offset portions 21. Said side frames are further provided with forwardly extending offsets 22 adjacent the upper forward corner of each thereof. The guard means further comprise a transversely extending guard member 23, having an eye portion 24 pivotally mounted on one of the forward offsets 22 and having a hook portion 25 engaging the other forward offset 22. Thus the frames are pivotally mounted on the back supporting or cover member 11 and are adapted to form an enclosure with the transverse member 23, which may be in the form of a sheet metal bar or strap, and the back supporting member 11.

Clips 26 are mounted on the seat portion 10 and are formed into a hooklike shape and cut away so as to form the hooks 27 and 28 with the intervening space or slot 29. The hook 28 is somewhat wider than hook 27. The frames 18 are engaged with the clips 26 so that the offsets 21 extend under the hooks 28 and the forward vertically extending portions 30 of the frames extend through the slots or openings 29, when the parts are in operative position.

Resilient means are provided for urging the frames 18 to swing in a direction away from each other, said means being shown as being in the form of coil springs 31, coiled around the vertically extending portions 19 of the frames, and having a hook 32 at one end of each thereof engaging around the lower member 20 of the frame 18 with which it is associated. The other end 33 of each spring 31 extends into an opening 34 in the back supporting cover member 11. It will be evident that if the parts are folded in the position shown in Fig. 2 with the frame members 18 and cross bar 23 nested in the recess 15 the same will be confined between the cover member 11 and the seat portion 10, and the device forming the subject matter of this invention will have the appearance of the ordinary toilet lid or cover, for which it is substituted. However, in order to bring the lower portions of the frames to such a position that the same can be engaged with the clips 26 without making these clips extend too high above the top of the seat portion 10, the offsets 21 are provided, and in order to accommodate these offsets and permit the back supporting portion 11 to assume a vertical position, when the

parts are in unfolded, operative position the recesses 35 are provided in the shoulder 14. It will be furthermore noted that when the device is unfolded the springs 31 will tend to move the frames 18 and the cross bar 23 to the dotted line position shown in Fig. 1 thus moving the same out of the way of the child when being placed in position on the device. After the frames 18 are engaged with the clips 26 and the hook 25 is engaged with the offset 22, the springs tend to hold the hook 25 in engagement with the said offset.

If desired, the pivoted catch 36 having the opening 37 engaging the projection 38 may be provided for holding the seat portion 10 and cover member 11 together when the device is folded up. The seat portion 10 is provided with an opening 39 therein and means is provided for adjusting the size of said opening by reducing the same, said means comprising an annular insert member 40 having a central opening 41. The edge of the opening 39 is bevelled as indicated at 42 and the outer edge of the insert 40 is oppositely bevelled. Clips 43 are provided for holding the insert member 40 in position in the opening 39.

Having thus described my invention, what I desire to claim and secure by United States Letters Patent is:

1. In a device of the character described, a seat portion, a back supporting portion hinged thereto and guard means comprising polygonal open side frames pivotally mounted on said back supporting portion.

2. In a device of the character described, a seat portion, a back supporting portion hinged thereto, guard means comprising side frames pivotally mounted on said back supporting portion and means on said seat portion detachably engageable with said side frames.

3. In a device of the character described, a seat portion, a back supporting portion hinged thereto and guard means comprising open side frames pivotally mounted on said back supporting portion and a transversely extending guard member pivotally mounted on one of said side frames and detachably engageable with said other side frame.

4. In a device of the character described, a seat portion, a back supporting portion hinged thereto and guard means comprising side members pivotally mounted on said back supporting portion and resilient means urging said side members toward a divergent position relative to each other.

5. In a device of the character described, a seat portion, a back supporting portion hinged thereto, and guard means comprising side frames pivotally mounted on said back supporting portion, said side frames having upper members, lower members and connecting portions, said lower members having

- downwardly offset portions and said seat portion being recessed to accommodate said offset portions when swung into position adjacent said back supporting portion.
5. 6. In a device of the character described, a seat portion having an opening therein and means for adjusting the size of said opening, comprising an annular member engaging in said opening and seating therein, said annular member and said seat portion having oppositely directed engaging shoulders.
7. In a device of the character described, a seat portion, a cover portion hinged thereto, said cover portion having a recess therein and 15 guard means comprising open side frames pivotally mounted in the recess in said cover portion, said guard means having downwardly extending offsets therein, and said seat portion having a shoulder adjacent said cover portion, said side frames being adapted to be folded within said recess when said cover portion overlies said seat portion and said shoulder having recesses receiving said offsets when said frames are folded within the recess 20 in said cover portion.
8. In a device of the character described, a seat portion, a back supporting portion hinged thereto, and guard frames having portions pivotally mounted on said back supporting portion, lower members detachably engageable with said seat portion, upper members and portions connecting the outer ends 25 of said upper and lower members.
9. In a device of the character described, a seat portion, a back supporting portion hinged thereto, and guard frames having portions pivotally mounted on said back supporting portion, lower members detachably engageable with said seat portion, upper members and portions connecting the outer ends 30 of said upper and lower members, said guard frames being provided with resilient means
- tending to swing said frames away from each other.
10. In a device of the character described, 45 a seat portion, a back supporting portion hinged thereto, guard frames having portions pivotally mounted on said back supporting portion, lower members detachably engageable with said seat portion, upper members and portions connecting the outer ends 50 of said upper and lower members, said guard frames being provided with resilient means tending to swing said frames away from each other and a cross member carried by the outer end of one guard frame and engageable with said other frame, said resilient means holding 55 said cross member in engagement with said last mentioned frame.
11. In a device of the character described, 60 a seat portion provided with an opening, a back supporting portion hinged thereto, side frames pivotally mounted on said back supporting portion and extending forwardly beyond said opening and a transverse guard member pivotally mounted on the forward end of one of said side frames and detachably engaging the forward end of the other side frame to extend transversely over said 65 seat portion forwardly of said opening.
12. In a device of the character described, 70 a seat portion, a back supporting portion hinged thereto; said back supporting portion having a recess therein, open guard frames hinged to said back supporting portion in 75 said recess, clips on the upper side of said seat portion detachably engageable with said guard frames and a transversely extending guard member connecting the forward ends 80 of said guard frames.

In testimony whereof, I hereunto subscribe my name this 19th day of August, 1927.

FRED C. IMMELE.
